UNITED STATES PATENT OFFICE.

EMIL KÄGI, OF WINTERTHUR, SWITZERLAND.

REFRIGERATOR.

Application filed October 4, 1922, Serial No. 592,188, and in Switzerland August 10, 1922.

This invention relates to refrigerators of the kind comprising a driving motor, a compressor, a condenser and a vapourizer, and has for its object to effect improvements in the construction of such apparatus.

According to the present invention the compressor is of the rotary type and is disposed coaxially with the driving motor outside the rest of the apparatus. Its suction and delivery spaces are arranged in a casting which is transverse to the motor shaft and is directly connected to the condenser. The condenser is preferably formed as a helical tube surrounding a chamber connected to the delivery space of the compressor and containing an oil-separating device. To prevent the passage of oil into the condenser, this chamber may be provided with transverse walls or partitions. The liquefied cooling medium is conveniently collected in a collecting tank disposed adjacent to the condenser, a throttle valve, which is automatically adjustable according to the liquid level in the tank, being provided to control the amount of cooling effected by the apparatus.

The vapourizer preferably consists of a sheaf of separate tubes, to which the cooling fluid is introduced by means of a distributor connected to the throttle valve.

A construction according to the invention is illustrated by way of example in the accompanying drawings, in which—

Figure 1 shows the apparatus in side elevation, and

Figure 2 a section on the line II—II of Figure 1.

The rotary compressor 1 contains a suction space 2, a rotor 3, radially movable vanes 4, a crescent shaped working space 5, and a delivery space 6. The driving motor is designated by 7, the condenser by 8, the throttle valve by 9 and the vapourizer by 10.

The connection between the compressor and the vertically arranged part of the apparatus is formed by the compressor casing which is arranged at right angles to the motor shaft.

The condenser 8 consists of a double-walled casing, between whose outer and inner walls there is a helical space 11, through which the cooling water passes upwards, a helical tube 12 being disposed therein, through which the cooling medium flows downwards in a direction opposite to the cooling water. The cooling medium from

the delivery space 6 is led through the oil separator 13 into a chamber 14, which is arranged inside the condenser helix and in which the separated oil collects, and proceeds therefrom past the transverse walls 15, the openings 16 and the outer wall of the chamber 14, through the passage 17 into the tube 12 constituting the condenser. The tube 12 may be made small according to the extent of the pre-cooling effected in the space surrounded by the outer wall of the chamber 14. From the condenser space 12 the cooling medium proceeds in a liquid condition through the passage 18 into the collecting tank 19 containing the throttle valve 9. The transverse walls 15 prevent the lubricating oil collecting in the chamber 14 from passing into the condenser when the machine is tipped. The lubricating oil is forced through passages not shown into the bearings of the compressor and into the suction space 2, where it is used for lubricating and sealing purposes. The cooling water is introduced through the passage 20 into the double-walled bottom of the condenser casing, flows therefrom into the conduit 11 and passes through the passage 21 into the compressor cooling space 22, whence it leaves the apparatus through the outlet 23. The outer wall of the condenser casing is made in two parts so as to allow the introduction of the tube 12 into the conduit 11 and to simplify opening up for the purpose of cleaning the cooling chamber.

The throttle valve consists of two tubular open-ended rotary sliders 24 and 25 disposed one within the other, which are provided with downwardly directed slots opening into the tube leading to the vapourizer 10 and are connected by means of levers 26 and links 27 to an annular float 28. The sliders 24 and 25 are rotated relative to one another by movement of the float, which varies its position according to the liquid level in the tank, so that the cross section of flow through the slots increases with rising liquid level, and conversely, decreases with falling liquid level. In this manner the amount of cooling fluid introduced in unit time to the vapourizer is automatically controlled according to the condenser output. In order to maintain the float constantly in a central position, the levers 26 are connected to links 29 to form a parallel linkage, of which the connecting point above the sliders moves in a vertical guide 30. Counterweights 31 are

connected to the sliders 24 and 25 so as to increase the adjusting force on the sliders when the liquid level falls.

The vapourizer consists of a number of 5 separate tubes 32 joined together to form a sheaf of tubes and closed at the bottom, and the cooling liquid is introduced into them through the passages 34 by means of a distributor 33, connected to the throttle 10 valve. The cooling fluid is led by the tubes 34 to the lower end of the vapourizer tubes and proceeds therefrom into the annular vapourizer space 35 between the tubes 32 and 34, whence it rises in the form of a 15 vapour into the collecting chamber 36, from which it is drawn through the tube 37 by the compressor. The employment of a vapourizer consisting of separate tubes has the advantages, that it possesses a great cooling 20 surface in a compact structure and, whilst avoiding excess of material which would prevent the transfer of heat, has an external form which allows a satisfactory circulation and simplifies thawing. The 25 distributor 33 may, if desired, be arranged in the lower part of the vapourizer, so that the cooling liquid is led directly to the lower end of each separate tube.

The machine operates in the following 30 manner. The cooling medium sucked in in gaseous form from the vapourizer, leaves the compressor at high pressure and flows through the oil separator into the pre-cooling chamber and thence into the condenser, 35 where so much heat is withdrawn from it by the cooling water that it liquefies. The liquefied cooling medium flows into the collecting tank, whence it proceeds into the vapourizer after passing the throttle valve. 40 The vapourizer in turn is in communication with the suction space of the compressor, whereby the cooling medium, owing to the fall of pressure produced, is vapourized and receives heat from outside. The cooling medium may be of any suitable kind.

Having now particularly described and ascertained the nature of my said invention and in what manner the same is to be performed, I declare that what I claim is:—

50 1. A refrigerator comprising an internally partitioned unitary casing, a horizontal shaft rotary compressor housed in the uppermost portion of said casing, a condenser chamber formed in a lower portion 55 of said casing, a helical condenser arranged

about the outside of said condenser chamber and connected to the compressor by said unitary casing enclosing the suction and pressure passages of said compressor, an evaporator disposed beneath said casing and 60 connected to said condenser through a refrigerant storage chamber formed in a still lower portion of said casing, and a throttle valve in said storage chamber for controlling the passage of refrigerant to 65 said evaporator in accordance with the level of the liquid in the storage chamber.

2. A refrigerator in accordance with claim 1 in which the condenser comprises an auxiliary casing which constitutes, with 70 the unitary casing of claim 1, a double wall structure, the walls of said structure forming between them a helical passage for the cooling medium, and a coiled pipe located in said passage and in which the refrigerant is 75 condensed.

3. A refrigerator in accordance with claim 1 in which the condenser comprises an auxiliary casing which consists with the unitary casing of claim 1 a double wall 80 structure, the walls of said structure forming between them a helical passage for the cooling medium, a coiled pipe located in said passage and in which the refrigerant is condensed and an oil separator located within 85 the space surrounded by the condenser coil, said space being in communication with the pressure side of the compressor and also with the interior of the condensing coil.

4. A refrigerator in accordance with claim 90 1 in which the condenser comprises an auxiliary casing which consists with the unitary casing of claim 1 a double structure, the walls of said structure forming between them a helical passage for the cooling 95 medium, a coiled pipe located in said passage and in which the refrigerant is condensed, an oil separator located within the space surrounded by the condenser coil, said space being in communication with the 100 pressure side of the compressor and also with the interior of the condenser coil, and transversely extending partitions located between the oil separator and the condenser coil to prevent the oil collected by the separator from passing into the condenser when the machine is tilted.

In testimony whereof I have affixed my signature.

EMIL KÄGI.
